GERMICIDAL BED APPARATUS FOR BEDRIDDEN PATIENTS

Edward Sokolik, New Brighton, Minn.

Application March 17, 1952, Serial No. 276,945

1 Claim. (Cl. 21—74)

My present invention relates to germicidal bedstead apparatus for bedridden (such as tubercular) patients, more particularly for patients under treatment in tubercular sanitariums.

A disadvantage of the present day sanitariums is that the exhaled air of the collective patients is homogenized and reinhaled by the patients and all other personnel associated with the patients, many of whom get infected.

The primary object of my invention is to provide a germicidal bed apparatus for use primarily in tubercular sanitariums, whereby the tubercular air exhaled by the patient is germicided as exhaled and simultaneously suctioned by an electrically driven fan or by the heating system and/or heating and air circulating system in which the exhaled air is preferably further conditioned by filtering, germiciding, degasifying and deodorizing, and finally homogenized with medicinal and aromatic fumes or vapors, an invention filed for under separate application Serial No. 336,749 filed February 13, 1953.

A further object is to provide the patient's bed with an adjustable inverted funnel to receive, and exhaust the exhaled air and to carry a germicidal lamp in the confines for germiciding the bedding around the patient's head.

Still further object is to provide a patient's bedstead with a flexible tubular air discharge conduit connected to the conduits of the heating and/or heating and air circulating system, thereby not only exhausting the air directly as exhaled by the patient, but permitting the bed to be moved from one place to another in the ward or room;

Another object is to provide a bed designed so that the patient may be attended from either side thereof and designed to exhaust the exhaled air as exhaled and to exhaust some air from near the ceiling above the patient's head that may partially be contaminated tubercularly;

Still another object is to provide the patient's bed with means for circulating the exhaled and germicidized air in the ward or room, when it is not desired to circulate the air through the heating and/or heating and circulating system.

In accordance with the aforementioned objects and other objects that will be apparent as the description progresses, the invention resides in the combination and arrangement of parts, and in the details of construction hereinafter described and claimed, it being understood that changes in the precise embodiment of the invention herein disclosed, may be made within the scope of what is claimed, without departing from the spirit of the invention.

In the drawings:

Fig. 1 illustrates a front view of the apparatus with fragmental sections.

Fig. 2 illustrates a side view of the apparatus with fragmental sections.

Fig. 3 is a view of the air receiving and conveying inverted funnel on line 3—3, Fig. 1.

Fig. 4 is a view on line 4—4, Fig. 1.

2

Fig. 5 is a cross-section on line 5—5, Fig. 1.

Fig. 6 is a cross-section on line 6—6, Fig. 1.

Fig. 7 is a cross-section on line 7—7, Fig. 1.

Fig. 8 is a plan view of the head hood.

Fig. 9 is a side view of the head hood.

Fig. 10 is a vertical section of one of the tubular tie-members showing the germicidal lamp disposed therein.

Fig. 11 is an end view of Fig. 10 showing the germicidal lamp mounted therein in a bracket.

Fig. 12 is a view on line 12—12, Fig. 1 showing the plate-like member with its slideways, the trough-like member mounted in the slideways and the inverted air funnel connected to the lower end of the trough-like member.

In the head end-frame of the bedstead 13, as shown, is embodied a vertical and horizontal system of tubular air conduits shown in Fig. 1. These air conduits are provided with ultra violet germicidal lamps 15 and 16 electrically equipped, whereby the bacteria in the infectious exhalations are germicided as they flow through the ultra violet rays thereof in said conduits 14.

Cooperating with this system of air conduits 14, is an inverted funnel 17, preferably vertically slideable and disposed above the patient's head, adapted to convey the

exhalations as exhaled by the patient thereinto; a flexible tubular conduit 18 for conveying the germ-free air from the system of tubular air conduits 14 into the heating and/or heating and air circulatory system, not shown; suction means associated with the said circulatory system for producing a flow of air into the funnel 17 and through the air conduits 14 and educting the germ-free air into the circulatory system and/or separate means for producing a flow of air associated directly with the air conduits 14 and educting the germ-free air into the patient's ward.

This separate means may be an electrically driven fan 19 or the germicidal lamp means 15 and 16, which inherently produces a limited flow of air in cooperation with the function of germiciding.

Also cooperating with the aforesaid devices of the apparatus, is a germicidal lamp 20 arranged in the inverted funnel 17 and cooperating with the ultra violet ray impenetrable head hood 21 in sterilizing the linen about the patient's head.

Comprised in the system of conduits 14, are the two bedstead pedestals 22 and 23 which are tubular in the upper portions thereof to afford flues for the conveyance of exhalations therethrough, and two horizontally superposed tubular tie-conduits 24 and 25, which have the inner surface thereof preferably of reflective characteristics to cooperate better with the ultra violet lamps 15 and 16.

The horizontal conduits 24 and 25 tubularly intersect the pedestals 22 and 23 so that tubular end-portions 26, like or similar to the transverse scope of the tie-conduits 24 and 25, are projected from the remote or opposite sides of the pedestals 22 and 23, thereby adapting the intersections 27 and 28 of the upper tie-conduits 25 for mounting the germicidal lamp 15 endwise in brackets 31, one in each end thereof, and thereby adapting the intersections 29 and 30 of the lower tie-conduits 24 for mounting the germicidal lamp 16 endwise in brackets 31 (Fig. 11). An electrically driven fan 19 is mounted on one of the end-portions 26, the other end-portion 26 being closed by a plug or preferably a cap 32. The end-portions 26 of the lower tie-conduits 24 are likewise closed with caps 33. The cap 32 and caps 33 are preferably screw-threaded applied and may be provided with apertures for electrical wires leading to the germicidal lamps

15 or 16. Wires (not shown) may connect the lamps 15 and 16 and may be disposed outside or inside one or both of the tubular pedestals 22 and 23. The lower tie-

conduits 24 is provided with an air inlet vent 36 preferably in the middle and front thereof.

The pedestals 22 and 23 are, each preferably, open at the top ends thereof and preferably provided with small funnels 37 and valves 38 therebeneath and valves 39 and 40 disposed between the tie-conduits 24 and 25. One or both of the pedestals 22 and 23 are also provided with an outlet duct 41 provided with a valve 42, and with an electrically driven fan 19 and a valve 43 connecting said fan 19 with the end-portion 26 of the tie-conduits 25. A bracket 44 supporting a pulley 45 is also fastened to the upper portion of one of the pedestals 22 or 23. Cleats 46 are provided on the lower portion of one or both of the pedestals 22 and 23.

A support tie-member 47 extends between the pedestals 22 and 23 and is secured thereto near the upper end-portions thereof and is provided generally in the middle thereof with a pulley 48. The lower portions of the pedestals 22 and 23 are preferably provided with tie-members 49.

Connecting this tubular conduit system 14 to the heating system and/or heating and air circulating system, is a flexible tubular conduit 18. It is interposed between the valve 42 on the outlet duct 41 and the dual elbows 50 and 51 flexibly swingably connected to each other by the coupling 52 and together connected to a conduit at 53 of the air circulating system. This manner of connection facilitates moving the bed about the ward. An outlet duct like duct 41 may also be provided on the other pedestal 23 to permit the bed to be on either side of the conduit indicated at 53.

Provided with this tubular conduit system 14 is the inverted funnel 17 provided with trough-like spout 54, disposed above the patient's head adjacent the front side of the tubular conduits 14. The funnel 17 receives the air as exhaled and the spout 54 conveys the same into the inlet vent 36 in the lower tubular tie-conduits 24. This combined funnel 17 and spout 54 are preferably adjustable vertically to facilitate the suctioning of the exhaled air, as indicated by arrows, when lowered and to facilitate nursing the patient, when raised. For this purpose the front side of the tubular system of conduits 14 is provided with an elongated rigid sheet 55 of suitable material extending up and down. The lower portion of this sheet may be widened to provide an air apron in which case the funnel 17 would not have to be provided with a wide apron 56. This apron affords an air barrier between the exhaled air and the air behind the conduit system 14 to facilitate the suctioning of the exhaled air into the funnel 17. The upper or narrower portion of the sheet 55 has the edges 57 thereof preferably folded to form therein slideways 58 (Fig. 5). The trough-like spout 54 is, preferably, semi-circular in vertical-section and provided with flanges 59 along its longitudinal edges. These flanges 59 slide in the slideways 58. The air is suctioned into the vent 36 whether the spout 54 is in raised or lowered position. The lower or open end of the spout 54 has preferably an outer flange 60 for securing thereto the bell of the funnel 17.

The bell of the funnel 17 has preferably a semi-circular vertical skirt 61 and a top 62 curving and merging into the skirt 61. The vertically-sectional side of the bell of the funnel 17 may be provided with a plane sheet 56 which is shown to extend down to the side members 63 of the bed, when in raised position. The raising and lowering is accomplished by a cord, cable or chain 64 or the like fastened to the eye 65 or to the closed top end of the spout 54. The other end of the cord may be provided with a hand-piece 66. The cord 64 is fastened to one of the cleats 46 when the funnel 17 is at the desired height. This funnel 17 is secured to the flange 60 of the spout 54 by rivet means 67 extending through the top 62. A germicidal lamp 20 is secured to the underside of the top

62 and is preferably operated by means of a safety switch. A head hood 21 generally of conoidal shape and of material impermeable by germicidal rays and provided with an air vent 68 inaccessible by the rays, is disposed over 5 the patient's head during the process of sterilizing the linen about the patient's head by the germicidal lamp 20. For this reason the conoidal type of hood 17 as described is preferable to a hood with pitched top and no skirt, because the attendant is not so apt to get burned by the 10 ultra violet rays of the germicidal lamp 20.

Operation

Operably, if the flexible air discharge conduit 18 and the fan 19 are connected to the pedestal 22, and the tubular air conduit system 14 of the head end-frame of the bed, is to convey the air through the heating and/or heating and air circulating system of the building, and not by and through the fan 19 back into the ward, the valve 39 and valve 43 are closed and the rest of the valves are open, 15 these are, the two valves 38, valve 42 and valve 40. A fan in the air circulating system of the building suctions the infected air into funnel 17 as indicated by arrows, thence through the spout 54 into the lower-tubular tie-conduits 24 through the vent 36 therein, thence through 20 the valve 40 into the upper tie-conduits 25, the upper tubular portion of the pedestal 22 and finally through the discharge conduit 18 into the air circulating system of the building. The infected air is germicided as it flows through the tie-conduits 24 and 25 by the germicidal lamps 25 15 and 16 respectively disposed therein. These lamps 15 and 16 are mounted preferably in brackets disposed in the 30 ends of the conduits 24 and 25 and are removable for the purpose of wiping off accumulated dirt on the lamps and in the conduits. If the air is to be circulated in the 35 ward by the fan 19, the valve 42 is closed and the valve 43 opened.

What I claim is:

A bedstead adapted for use with patients having infectious exhalations, including in the head end-frame of the 40 bedstead, tubular air conduit means provided with ultra violet ray lamp means, electrically equipped, said conduit means having an air inlet leading to the lamp means and an air outlet leading from the lamp means and communicating with means for producing a flow of air through the air conduit means; a hemi-funnel superposed above the patient's head to facilitate the conveyance of the patient's exhalations into the said hemi-funnel, said hemi-funnel being in air-flow communication with the air inlet and adapted to be adjustably elevated, and including a hemi-bell portion and a hemi-spout portion closed at the free 45 end thereof, but having the hemi-side open and in air flow communication with the air inlet at any predetermined elevation of said hemi-funnel, said hemi-spout having edges adapted to afford vertical slide means; air baffle 50 extending vertically along the end-frame and having an opening adapted to register with the said air inlet and having edges adapted to afford vertical slide means adapted slideably to cooperate with the slide means of the hemi-spout; means mechanically in communication with the hemi-funnel and adapted to be manually operable 55 thereby to elevate the hemi-funnel.
